Primary Examiner — Michael C Stout*Assistant Examiner* — Fitzgerald L Butac(74) *Attorney, Agent, or Firm* — Ulmer & Berne LLP(57) **CLAIM**

The ornamental design for a retention tray assembly for a food dispensing machine, as shown.

DESCRIPTION

FIG. 1 is a rear right perspective view depicting a retention tray assembly for a food dispensing machine;

FIG. 2 is a rear elevation view depicting the retention tray assembly of FIG. 1;

FIG. 3 is a front elevation view depicting the retention tray assembly of FIG. 1;

FIG. 4 is a right side view depicting the retention tray assembly of FIG. 1;

FIG. 5 is a left side view depicting the retention tray assembly of FIG. 1;

FIG. 6 is a top elevation view depicting the retention tray assembly of FIG. 1;

FIG. 7 is a bottom elevation view depicting the retention tray assembly of FIG. 1;

FIG. 8 is a front left perspective view depicting the retention tray assembly of FIG. 1;

FIG. 9 is a front right exploded perspective view depicting the retention tray assembly of FIG. 1; and,

FIG. 10 is a rear left exploded perspective view depicting the retention tray assembly of FIG. 1.

The details shown in broken lines in the figures form no part of the claimed design for the retention tray assembly for a food dispensing machine.
